UNITED STATES PATENT OFFICE.

FELIX Q. RAST, OF NEW YORK, N. Y.

COIN-OPERATIVE DEVICE.

Application filed March 17, 1927. Serial No. 176,073.

My invention relates to coin-operating devices and refers particularly to devices of this character adapted for the sale of commodities.

5 The object of my invention is a device having a plurality of compartments, each having a door capable of locked closure, the locking mechanism being released upon the insertion of a coin in order to allow access to the compartment, the compartments having a door which is not operated by the inserted coin but which is capable of being opened independently thereof.

10 My invention, therefore, presents a device in which a plurality of commodities may be contained, each in a separate compartment, access to each commodity being accomplished by the insertion of a coin in a designated slot, or opening; and means whereby commodities 15 may be introduced into the compartments without reference to a coin insertion.

15 In the particular form of the device of my invention shown in the accompanying drawings, commodities may be introduced into the rear of the compartments, while access to the commodities upon the part of the purchaser is through the forward part of the compartments. This construction allows of the device being placed within the space 20 formed by the so-called "Serve-a-Door" construction, that is within the space between a door opening into a room and a door opening into the public corridor, thus allowing the introduction of commodities from the corridor without disturbing the occupant of the room, and even if access to the room is not possible.

25 My invention is directed to the particular mechanism incident to the production of the foregoing described operations and includes mechanism for the accomplishment of the other desirable results as will be evident upon a consideration of my specification and the accompanying drawings.

30 In the accompanying drawings illustrating one form of the device of my invention, similar parts are designated by similar numerals.

35 Figure 1 is a top view of one form of the device of my invention.

Figure 2 is a front view of Figure 1 partly broken away for purposes of clearness of description.

40 Figure 3 is a cross-section through line 55 3-3 of Figure 4.

Figure 4 is a cross-section through line 4-4 of Figure 3, with the front door closed and locked and the back open.

Figure 5 is a view like Figure 4 with the front door open and the back closed. 60

Figure 6 is a fragmentary horizontal cross-section showing the operation incident to the insertion of coins of different diameter taken on the line 6-6 of Figure 4.

65 The particular form of the device of my invention shown in the accompanying drawings comprises, a casing having the sides 10, 10, the front 11, the back 12, the top 13 and the bottom 14. The back 12 is hingedly attached to the bottom 14 at 15, 15.

70 Fixedly attached to the bottom 14 is a metal strap 16, carrying the upwardly extended supports 17, 18, 19. A revoluble rod 20 passes through openings in the supports 17, 18, 19, and carries a fixedly attached coin rest which consists of a plurality of bases 21, 21, and the lower upturned edges 22, 22. The rod 20 also carries a plurality of extended spaced pins 23, 23. One coin rest extends from the support 17 toward the support 18 75 but is spaced therefrom. Another coin rest extends from support 18 to support 19, and the third coin rest extends from the support 19 toward a side wall 10. A coiled spring 24 is attached to the side wall 10 and the rod arm 25, tending to maintain the coin rests in their upward position. 80

85 A rod 26 extends through holes in the upper portions of the supports 17, 18 and 19 and carries a plurality of revoluble sleeves 27, 27. 90

95 Each sleeve 27 carries a fixedly attached coin operating arm 28 and a fixedly attached returning arm 29, the latter being attached by means of a spiral spring 30 to a rod 31 passing through holes in the supports 17, 18 and 19, tending to pull the coin operating arm 28 toward the front of the casing.

100 Pivotedly carried by the coin operating arm 28 at 32 is a rocker arm 33 having the recess 34 and the extended member 35.

105 Fixedly attached to the rod 26 is a locking arm 36 having a hook extremity 37.

110 Fixedly attached to the rod 26 is a closure arm 38.

The operating mechanism comprises a link movement consisting of the link 39 fixedly attached to the revoluble rod 20 and pivotally attached at 40 to the link 41. The link 41 is pivotally attached to the angle link 42 at 43. Pivotedly attached to the link 42 at 44 is the

rod 45 extending through the casing front 11 and terminating in the knob 46.

Extending transversely of the device and above the rod 26 is a platform 47 having a plurality of upwardly extended walls 48, 48, thus forming a plurality of compartments 49, 49.

Hingedly attached to the casing front 11 is a plurality of doors 50, 50, each covering one of the compartments 49, 49. Each door 50 carries a locking hook 51 capable of movement over a recess 52 of the platform 47, when the door is in closed position. Each door 50 carries a frame 53 open at the top and capable of receiving a printed card 59. The extreme 50^A is shown open in Figures 3 and 4.

A coin receiving slot 54 is positioned in the front 11 below each door 50, and a coin return opening 55 positioned below each door 20 opens into a receptacle having the inclined bottom 56.

The hinged back 12 is attached to the upper part of the device by means of a chain 57 to limit the downward movement of the back 25 and carries a lock 58 capable of locking the back in closed position.

Assuming that the doors of the device are closed, the operation of the device is as follows:

30 A coin of the proper size 60 is passed through a slot 54 and falls upon the base 21 and is held in position by the turned edge 22. The handle 46 is then pulled outwardly operating the link movement 42, 41, 39 and 35 revolving the bar 20. This movement brings the coin 60 in abutment with the coin operating arm 28, a further revolution of the bar 20 causing a revolution of the sleeve 27 moving the member 36 downwardly and releasing 40 the hook 51 of the door 50 allowing the door to swing outwardly and allowing access to the compartment 49. This revolution of the sleeve 27 causes the rocker arm 33 to move downwardly, the spring 30 forcing the recess 34 to engage the bar 31 thus preventing the locking arm from upward movement into locking position. The same movement of the sleeve 27 causes the closure arm 38 to move downwardly the free extremity of which 50 moves across the coin slot 54 and prevents the introduction of another coin until the door 50 is closed. The movement of the coin rest 21, 22 throws the coin into the lower portion of the casing.

55 When it is desired to introduce a new commodity into the compartment 49, the back 12 is unlocked and lowered, a commodity introduced, the door 50 is pushed inwardly, the rocker arm 33 is pressed downwardly and released from the contact with the bar 31. The spring 30 then revolves the sleeve 27 causing the hook 37 of the locker arm 36 to pass through the recess 52 and connect with the hook 51 of the door 50 retaining the door in locked and closed position.

The same revolution of the sleeve 27 causes the arm 38 to move upwardly allowing the introduction of another coin.

The back 12 is then closed and locked.

The coin openings 54, 54 are of the exact width of the coin intended to be inserted. If a smaller coin 62 is inserted it will not be large enough to span the space between the casing front 11 and the extremity of the coin rest 21, 22, and hence will fall through the space 61 upon the inclined bottom 56 and can be recovered through the opening 55.

It will be noted from the above that commodities can be introduced into the several compartments through the rear of the device 80 and that access can be had to any particular commodity through the front of the device by the insertion of a coin into the proper coin slot.

I do not limit myself to the particular size, shape, number or arrangement of parts as shown and described, as these are given simply for purposes of clearly describing the device of my invention.

What I claim is:

1. In a coin-operative device, in combination, a casing, a plurality of compartments within the casing, a hinged door covering the front opening of each compartment, a coin slot for each front door, a revoluble rod passing longitudinally of the device and below the compartments, a coin rest fixedly attached to said rod beneath each compartment capable of receiving a coin passed through a coin slot, means operable exteriorly of the casing revolving said rod, means whereby the revolution of said rod will cause a coin deposited upon a coin rest to unlock a front door, means inoperative from the front of the casing and operative from the rear of the casing for locking each front door, means preventing the insertion of a coin into a coin slot when its front door is open and a door covering the rear openings of the compartments.

2. In a coin-operative device, in combination, a casing, a plurality of compartments within the casing, a hinged door covering the front opening of each compartment, a coin slot for each front door, a revoluble rod passing longitudinally of the device and below the compartments, a coin rest fixedly attached to said rod beneath each compartment capable of receiving a coin passed through a coin slot, means operable exteriorly of the casing revolving said rod, a non-revoluble second rod extending longitudinally of the device and below the compartments, a revoluble sleeve carried by said second rod below each compartment, a coin operating arm carried by each sleeve, means whereby the revolution of the first mentioned revoluble arm will cause a coin carried by a coin rest to abut upon a coin operating arm revolving its sleeve and unlocking a front door, means in-

operative from the front of the casing and operative from the rear of the casing for locking each front door, means preventing the insertion of a coin in a coin slot when 5 its front door is open and a door covering the rear openings of the compartments.

3. In a coin-operative device, in combination, a casing, a plurality of compartments within the casing, a hinged door covering the 10 front opening of each compartment, a coin slot for each front door, a revolute rod passing longitudinally of the device and below the compartments, a coin rest fixedly attached to said rod beneath each compartment capable 15 of receiving a coin passed through a coin slot, means operable exteriorly of the casing revolving said rod, a non-revolute second rod extending longitudinally of the device and below the compartments, a revolute 20 sleeve carried by said second rod below each compartment, a coin operating arm carried by each sleeve, a locking arm carried by each sleeve, means whereby the revolution of the first mentioned arm will cause a coin carried by a coin rest to abut upon a coin operating arm revolving its sleeve and causing the locking arm to move from locked engagement with a front door, means inoperative from 25 the front of the casing and operative from the rear of the casing for causing said locking arm to move from unlocked to locked engagement with a front door and a door covering the rear opening of the compartment.

4. In a coin-operative device, in combination, a casing, a plurality of compartments within the casing, a hinged door covering the front opening of each compartment, a coin slot for each front door, a revolute rod passing longitudinally of the device and below the 30 compartments, a coin rest fixedly attached to said rod beneath each compartment capable of receiving a coin passed through a coin slot, means operable exteriorly of the casing revolving said slot, a non-revolute second rod 35 extending longitudinally of the device and below the compartments, a revolute sleeve carried by said second rod below each compartment, a coin operating arm carried by each sleeve, a locking arm carried by each sleeve, means whereby the revolution of the first mentioned arm will cause a coin carried by a coin rest to abut upon a coin operating arm revolving its sleeve and causing the locking arm to move from locked engagement with a front door, means inoperative from 40 the front of the casing and operative from the rear of the casing for causing said locking arm to move from unlocked to locked engagement with a front door and a door covering the rear opening of the compartment.

5. In a coin-operative device, in combination, a casing, a plurality of compartments

within the casing, a hinged door covering the front opening of each compartment, a coin slot for each front door, a revolute rod passing longitudinally of the device and below the compartments, a coin rest fixedly attached to said rod beneath each compartment capable of receiving a coin passed through a coin slot, means operable exteriorly of the casing revolving said rod, a non-revolute second rod extending longitudinally of the device and below the compartments, a revolute 70 sleeve carried by said second rod below each compartment, a coin operating arm carried by each sleeve, a locking arm carried by each sleeve, means whereby the revolution of the first mentioned arm will cause a coin carried by a coin rest to abut upon a coin operating arm revolving its sleeve and causing the locking arm to move from locked engagement with a front door, means carried by each sleeve maintaining the locking arm in unlocked position, means inoperative from the front of the casing and operative from the rear of the casing for causing said locking arm to move from unlocked to locked engagement with a front door and a door covering the rear opening of the compartment.

6. In a coin-operative device, in combination, a casing, a plurality of compartments within the casing, a hinged door covering the front opening of each compartment, a coin slot for each front door, a revolute rod passing longitudinally of the device and below the compartments, a coin rest fixedly attached to said rod beneath each compartment capable of receiving a coin passed through a coin slot, means operable exteriorly of the casing revolving said rod, a non-revolute second rod extending longitudinally of the device and below the compartments, a revolute 95 sleeve carried by said second rod below each compartment, a coin operating arm carried by each sleeve, a locking arm carried by each sleeve, means whereby the revolution of the first mentioned arm will cause a coin carried by a coin rest to abut upon a coin operating arm revolving its sleeve and causing the locking arm to move from locked engagement with a front door, means carried by each sleeve maintaining the locking arm in unlocked position, means inoperative from the front of the casing and operative from the rear of the casing for causing said locking arm to move from unlocked to locked engagement with a front door, means carried by each sleeve maintaining the locking arm in unlocked position, means inoperative from the front of the casing and operative from the rear of the casing for causing said locking arm to move from unlocked to locked engagement with a front door, means preventing the insertion of a coin into a coin slot when its front door is open, means whereby a coin other than that of a predetermined size will not operate the device and will be delivered exteriorly of the device and a door covering the rear openings of the compartments.

Signed at New York city, in the county of New York and State of New York this 16th day of March, 1927.

FELIX Q. RAST.
